UNITED STATES PATENT OFFICE.

ERNESTO STASSANO, OF TURIN, ITALY.

ELECTRIC FURNACE.

1,105,859.

Specification of Letters Patent.

Patented Aug. 4, 1914.

Application filed October 15, 1913. Serial No. 795,382.

To all whom it may concern:

Be it known that I, ERNESTO STASSANO, a subject of the King of Italy, residing at Turin, Italy, have invented certain new and useful Improvements in Electric Furnaces, of which the following is a specification.

This invention relates to the electric furnaces, particularly to the electric furnaces of the type described in my U. S. Patents Nos. 1,024,657 and 1,059,499, in which the melting chamber being carried by a universal suspension member or flexibly suspended from above so that its axis is capable of describing a cone, a continuous or intermittent conical movement can be imparted to the said axis with the result that the charge is stirred up as would be in a rotary furnace while the furnace is a merely oscillating one, and has for its object an improvement which consists in means that permit the furnace chamber to be adjusted by hand in order to regulate the height of its casting outlet or tap hole.

If the furnace chamber be arrested in a position wherein the tap hole or outlet is elevated so that the molten metal can not flow out until the tap hole is lowered, it is not easy, by aid of a motor, to regulate the rotation of the wheel that is at the base of the chamber and rocks the depending pivot of the chamber, so as to gradually lower the tap hole and to stop the rotation at any moment. This drawback is obviated by the present invention by adopting a hand control in place of the control by an electric motor when imparting to the said actuating wheel the small angular displacements necessary for bringing the tap hole into the desired position.

In the accompanying drawing is shown, by way of example, one form of the invention as applied to a furnace suspended in the manner described in my U. S. Patent No. 1,059,499, in which the chamber is carried by a universal suspension member so that its axis can describe a cone the apex of which is above said chamber.

Figure 1 shows diagrammatically the furnace with its chamber in a position in which the molten metal can not be released; Fig. 2 shows the hand control applied to the same furnace and Fig. 3 is a detail of the controlling device.

As shown in Figs. 2 and 3, the toothed wheel 18 meshing with the wheel 17, that effects by its rotation the rocking of the furnace chamber, is fixed to a shaft 19 which may be actuated through gearing 20 by a shaft 21 operated directly by the electric motor 22.

According to the present invention on the shaft 21 is mounted to slide, but constrained to rotate with it, a sleeve 23 which can be shifted by means of the forked member 24 carried by a bell-crank lever 25 which in turn can be operated, for example, by means of rod 26 and pedal 27.

The sleeve 23 is provided with a toothed wheel or pinion 28 which by operating lever 25 can be made to mesh with a wheel 29 which can be turned with the aid of suitable gear 30 by hand wheel 31. Consequently while normally the lever 25 under the action of a spring as shown, or other suitable means, remains in the position represented in Fig. 3, the wheel 28 is out of gear with the wheel 29 and the furnace is rocked by means of motor 22. By pressing on the pedal 27, wheel 28 is brought into mesh with wheel 29 so that when the hand wheel 31 is turned a movement is transmitted to wheel 18 in gear with wheel 17 which directly oscillates the chamber. Supposing the chamber has been stopped in the position it has in Fig. 1, it is necessary merely to turn the hand wheel 31, while pressing on the pedal 27, in order to turn the chamber so as to lower gradually the tap hole. It will be understood that it is possible in this way to regulate the casting by lowering the tap hole to the extent necessary to allow the desired amount of metal to flow out.

What I claim is:—

1. In an electric furnace with an oscillating melting chamber, means for imparting motion to the melting chamber by power and by hand at will, comprising a rotatable member controlling said chamber, a shaft arranged to transmit rotation to the said member, a pinion sliding on said shaft for engaging a hand-controlled wheel, and means for bringing said sliding pinion in engagement with the hand-controlled wheel.

2. In an electric furnace with an oscillating melting chamber, means for imparting motion to the melting chamber by power

and by hand at will, comprising a rotatable member controlling said chamber, a shaft arranged to transmit rotation to the said member, a pinion sliding on said shaft for 5 engaging a hand-controlled wheel, and a pedal lever for bringing said sliding pinion in engagement with the hand-controlled wheel.

In testimony whereof I affix my signature in presence of two witnesses.

ERNESTO STASSANO.
